UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE TRUNK CIRCUITS.

Application filed May 19, 1922. Serial No. 562,191.

The present invention relates in general to telephone trunk circuits but is more particularly concerned with automatic trunk circuits, and the general object of the invention is to provide a novel and improved trunk circuit for connecting a manual exchange with an automatic exchange.

In trunk circuits of this character it often occurs that when the operator in the manual exchange plugs into a trunk circuit, a false impulse of current is unintentionally sent over the trunk extending to the switching equipment in the automatic office, and due to this false impulse the operator fails to obtain the desired connection. A particular object of the invention is to eliminate the possibility of a false impulse of current being sent over a trunk circuit of this character under the conditions above set forth.

Another object of the invention is to provide means for signalling the operator in the manual exchange if she fails to restore the dial key in her cord circuit to normal after having set up the call and before the called subscriber answers.

A further object of the invention is to provide an improved repeater circuit whereby the setting of the operator's calling device prepares the impulsing circuit instead of the first impulse sent by the calling device as has been the case heretofore.

There are other objects of the invention which, together with those specifically pointed out above, will be described hereinafter reference being had to the accompanying drawings forming part of this specification.

Referring now to the drawings, Figs. 1 and 2 show by means of the usual circuit diagrams sufficient of the apparatus in the system to enable the invention to be readily explained and understood.

Referring now more particularly to Fig. 1, the equipment shown is in the manual exchange. The reference character A indicates a manual substation of the ordinary type having the usual line equipment at the exchange. One of the operator's cord circuits is indicated by the reference character O. At the right of the sheet, indicated by reference character D, there is shown a trunk line comprising conductors 70 and 71 which extends to the distant automatic exchange. This trunk line is pro-

vided at the manual exchange with a group of relays which serve to repeat impulses over the trunk line in a manner similar to an ordinary two wire repeater. The trunk line terminates at the manual exchange in the jack J.

In Fig. 2, the trunk line mentioned terminates in the incoming first selector E. The selector E is a vertical and rotary switch of the usual Strowger type and is operated according to the two wire system of control.

Accessible to the first selector E is a plurality of connectors such as the one indicated in the drawings and designated by the reference character H. Only a portion of the circuits of the connector H have been shown. However, it will be understood that this connector is of the ordinary Strowger vertical and rotary two wire type.

The connector H has access to subscribers' lines in the automatic exchange. One of these being that of the substation A' terminating in the bank contacts 213-215, inclusive. The substation A' is of the usual automatic type being provided with the calling device S for controlling the central office switches.

The line of the substation A' terminates at the exchange in the individual line or trunk selecting switch C. The line switch C is of the usual rotary type whose wipers have no normal position always remaining in engagement, when idle, with the bank contacts associated with the trunk line last used.

Although only a first selector has been shown in the drawings, it will be understood that the size of the exchange is immaterial, and may be increased in the usual manner by inserting selectors between the first selector E and the connector H.

At D', Fig. 1, is shown a modification of the trunk circuit D which has a higher grade of transmission than the trunk circuit D.

Having described the apparatus shown in the drawings, its detailed circuit operation when the subscriber at substation A' in the manual exchange desires to call a subscriber at substation A in the automatic exchange will now be explained.

When the receiver is removed at substation A, a circuit is closed for the line relay 105 15 which attracts its armature 18 and lights

the lamp L in the usual manner. This operation signals the operator at whose position the answering jack J appears, and she will respond to the call by inserting the answering plug of an idle cord circuit, the cord circuit O for example, in answering jack J. When the plug is inserted in the jack, the cut off relay 16 is energized, the circuit of the line relay 15 is broken and the line lamp L is extinguished. At the same time a circuit is completed over the sleeve of the cord for answering supervisory lamp L', but since the receiver is off the hook at substation A, the supervisory relay 25 will at once operate to shunt out the lamp L' to prevent it lighting at the present time. The operator may now throw her key K into listening position in order to answer the calling subscriber and ascertain what number is desired. Having found that the desired party is the subscriber at substation A' in the distant automatic exchange, the operator will test the jacks associated with the trunk lines extending to such exchange with the tip of the calling plug P' in the usual manner, and will insert the plug into the first idle jack. Assuming that the trunk line shown in the drawings is the first idle trunk line, the calling plug P' will be inserted into the jack J'. A circuit is thereby established for the sleeve relay 55 in series with the supervisory lamp L'. Upon energizing, relay 55 at armature 64 closes the circuit of the polarizing winding of the electro-polarized relay 51, at armature 63 closes a point in the operating circuit extending to the distant automatic exchange, and at armature 65 closes a point in a chain circuit which will be described subsequently. Another result of the insertion of the calling plug P' into the jack J' is that a circuit is completed for the relay 54 extending from ground through the upper right hand winding of the repeating coil of the cord circuit, by way of springs 36 on key K', tip of plug P', tip of jack J', through the winding of relay 54 and thence to battery by way of the normally closed springs controlled by armature 56. Relay 54 is energized over this circuit and operates to place a bridge across the trunk conductors 70 and 71. This bridge may be traced from trunk conductor 70 by way of armature 62 and its front contact, armature 60 and its back contact, through the lower winding of the electro-polarized relay 51, through the winding of relay 53, to trunk conductor 71. Closure of the above traced bridge causes the energization of the line relay 150 of the incoming first selector E in the automatic exchange. Relay 150, upon energizing, at its armature 155 closes a circuit for the slow acting relay 151. Upon operating, the latter relay at armature 156 opens a point in the circuit of the release magnet 158, at the front contact of this armature prepares the

operating circuit of the selector E, and at armature 170 prepares a circuit for the switching relay 154. The relay 53 in the trunk circuit D is energized in series with the line relay 150 of the first selector E and operates at its armature 61 to short circuit the impulse springs 62 on the line relay 54 thereby establishing a locking circuit for itself exclusive of the contact 62 on the line relay. This short circuiting of spring 62 and its working contact by the energization of relay 53 prevents a false interruption being produced in the circuit of the line relay 150 of the selector E in case the circuit of the line relay 54 should happen to be momentarily opened when the calling plug is inserted into the jack J'. This occurs sometimes at the instant of plugging in due to imperfect contact between the plug and jack or to unskillful manipulation by the operator. It should be mentioned at this time that the electro-polarized relay 51 in the repeater D is not operated at this time as the effect of the upper polarizing winding neutralizes the effect of the lower winding.

The foregoing operations have all taken place automatically in response to the insertion of the plug into the jack J'. The operator will now throw the calling device key K' in order to connect the calling device S' in the control circuit of the line relay 54 of the repeater D, and will then proceed to call the digits in the number of the substation A'. When the key K' is thrown, it will be seen that the springs of the calling device S' are substituted for the upper right hand winding of the repeating coil in the cord circuit O in the circuit of the line relay 54. Upon the forward movement of the calling device for the first digit of the desired number, the spring 37 on the calling device S' is operated and engages its working contact. By this operation a circuit is completed extending from ground by way of the working contact of spring 37 and the said spring, spring 38 of key K' and its working contact, ring of plug P', ring of jack J', back contact and armature 57, and through the winding of the relay 52 to battery. Upon energizing, relay 52 at its armature 60 places a direct bridge across the trunk conductors 70 and 71 exclusive of the windings of relays 51 and 53. The relay 53, of course, retracts its armature 61 thereby opening its own locking circuit. When the calling device dial is released, in its restoration to normal, a series of interruptions is produced in the circuit of the line relay 54 of the repeater D. By the deenergizations of this relay this impulsive series is repeated to the line relay 150 of an incoming first selector E in the automatic exchange.

The series of interruptions produced in the circuit of line relay 150 of the selector E causes this relay to be deenergized a corre-

sponding plurality of times each time sending an impulse of current to the vertical magnet 159 in series with the slow acting relay 152. Magnet 159 operates to raise the switch shaft carrying the switch wipers 170-172, inclusive, step by step until the said wipers are brought opposite the level of bank contacts corresponding to the number of interruptions in the digit dialled. The slow acting relay 152 is energized in series with the vertical magnet 159, and upon the first movement of the switch shaft, when the off normal springs are shifted, operates to complete a circuit for the stepping relay 153. Relay 153, upon operating, at its armature 161 establishes a locking circuit for itself and at its armature 162 prepares a circuit for the rotary magnet 163. Shortly after the termination of the vertical movement of the switch the slow acting relay 152 deenergizes thereby completing the circuit of the rotary magnet 163. The rotary magnet 163 operates to rotate the switch shaft thereby bringing the switch wipers into engagement with the first set of bank contacts on the level to which they were raised by the vertical magnet, and at armature 164 opens the locking circuit of the stepping relay 153. Upon retracting its armature, relay 153 opens the circuit of the rotary magnet 163 which likewise deenergizes. The operation of the selector E now depends upon whether its wipers 170-172, inclusive, are associated with an idle trunk line or not. Assuming the associated trunk line is busy, there will be a ground potential upon the test contact engaged by the test wiper 171 and the stepping relay 153 will be energized to close a locking circuit for itself and to complete the circuit of the rotary magnet. Magnet 163 causes the switch wipers to be rotated into engagement with the next set of bank contacts in the selected level and opens the circuit of the stepping relay 153, which deenergizes, opening the circuit of the rotary magnet, which deenergizes also. The alternate operation of the stepping magnet 153 and the rotary magnet 163 continue until the switch wipers are brought into engagement with a set of bank contacts associated with an idle trunk line. It will be assumed that the trunk line shown in the drawings terminating in the bank contacts 173-175, inclusive, is the first idle trunk line. Immediately upon the wipers of the switch being rotated into engagement with this set of bank contacts the rotary movement of the switch ceases and the switching relay 154, which has been short circuited during the operation of the switch, is energized in series with the stepping relay 153. Relay 154, upon operating, at its armature 167 grounds the test contact 174 in order to busy the seized trunk line, at armature 168 opens the circuit of the

slow acting relay 151, at armatures 166 and 169 disconnects the windings of the line relay 150 from the trunk conductors 70 and 71, and at the front contacts of these armatures extends the said conductors by way of wipers 170 and 172, bank contacts 173 and 175, to the upper and lower windings of line relay 201 of the connector H.

Returning now to the operation of the apparatus in the manual exchange, when the calling device dial reaches its normal position, the circuit of the relay 52 is opened, and this relay deenergizes to replace the windings of the relays 51 and 53 in the bridge across conductors 70 and 71. The relay 53 again energizes to short circuit the impulse springs 62 and to establish a locking circuit for itself.

When the calling device S' is operated for the next digit of the desired number, the relay 52 operates as before described to open the circuit of the relay 53, and a series of interruptions is produced in the circuit of the line relay 54 of the repeater D. By the deenergizations of the line relay 54 this impulse series is repeated to the line relay 201 of the connector H in the automatic exchange. The deenergizations of the line relay 201 in response to these interruptions control the vertical magnet of the switch in stepping the switch shaft carrying the wipers 210-212, inclusive, step by step until the said wipers are brought opposite the level of bank contacts in which is located the contact set associated with the line of the substation A'.

In the manual exchange, when the finger hole dial returns to normal, the relay 52 deenergizes to again replace the relay 53 in bridge of the trunk conductors 70 and 71, and this latter relay operates as before to re-establish its locking circuit.

The operator may now operate her calling device S' in accordance with the next and final digit of the desired number. By this operation the relays 52 and 54 in the repeater D cause the series of interruption to be produced in the circuit of the line relay 201 in the connector H, and the line relay 201 deenergizes a plurality of times to control the rotary magnet of the connector in rotating the wipers of the switch into engagement with the set of bank contacts associated with the line of the substation A', which, as shown in the drawings, terminates in contacts 213-214, inclusive.

Assuming that the line of the substation A' is idle at the present time, the relay 220 in the line switch C will be operated to clear the line of its normal battery and ground connections in the usual manner and ringing current will be automatically projected out on the called line to signal subscriber at substation A'. When the receiver is removed at substation A', the signalling

- operation ceases and by the operation of the ring cut off relay in the connector talking current is supplied to the called substation from the winding of back bridge relay 200.
- 5 Relay 200, is energized over the called line loop and, upon operating, at armatures 204 and 205 reverses the connections of the line relay 201 with regard to the trunk conductors 70 and 71 whereby the current flow through
- 10 the windings of the relays 51 and 53 in bridge of these trunk conductors in the repeater D is reversed. This reversal of current flow causes the operation of the electro-polarized relay 51 in the repeater D. Upon operating,
- 15 relay 51 at armature 58 closes the circuit of the relay 50. The latter relay, upon operating, at armature 57 disconnects the relay 52 from the ring side of the trunk and at armature 56 places the line relay 54 in series
- 20 with the resistance 67 in bridge of the ring and tip sides of the trunk. Assuming that the operator has already restored key K' which will ordinarily be the case, this operation causes the energization of the supervisory relay 30 in the cord circuit O. Relay 30 operates to place a shunt around the supervisory lamp L² which is extinguished. By the effacement of the lamp L² the operator is informed that the called subscriber
- 25 has answered. Conversation between the two subscribers may now take place in the ordinary manner, which will be understood without further consideration.
- Should the operator fail to return the key K' to normal position before the called subscriber answers, the bridging of the line relay 54 across the ring and tip sides of the trunk by the energization of relay 50 causes a circuit to be completed extending from
- 30 ground through the impulse springs of the calling device S', spring 39 of key K' and its working contact, tip of plug P', tip of jack J', through the winding of relay 54, front contact and armature 56, resistance 67,
- 35 ring of jack J', ring of plug P', working contact of spring 38 and the said spring, spring 37 of the calling device S' and its resting contact, and through the winding of relay 33 to battery. The relay 33 operates over
- 40 this circuit and at its armature 34 connects a lead from the signalling machine T to the tertiary winding of the induction coil associated with the operator's head set. A tone is thus given to the operator informing her
- 45 that the calling device key K' is off normal. Upon hearing this tone, the operator will restore the key K' to normal whereupon the operation will proceed in the manner already described.
- 50 The manner in which the connection is released will now be described. The replacement of the receiver at the calling substation A causes the lighting of the supervisory lamp L'. When the receiver is
- 55 replaced at substation A', the back bridge

relay 200 in the connector H deenergizes and reverses the direction of current flow over the trunk line incoming to the selector E and through the lower winding of electro-polarized relay 51 in bridge of said trunk line at repeater D to normal. The two windings of relay 51 now oppose each other, the said relay retracts its armature and the circuit of the relay 50 is opened. The deenergization of relay 50 disconnects the bridge across the ring and tip sides of the jack J' whereby the circuit of the supervisory relay 30 in the cord circuit O is opened. Upon deenergizing, relay 30 opens a shunt around the supervisory lamp L² thereby causing this lamp to be lighted. Upon the operator receiving the disconnect signals, she will remove the plugs P and P' from the jack J and J'. Upon the removal of the plug P from the jack J the line circuit at substation A is restored to normal. By the removal of the plug P' from the jack J' the circuit of the line relay 54 as well as the sleeve relay 55 is opened. The deenergization of the line relay 54 allows the armature 62 on the line relay to fall back. The deenergization of the sleeve relay 55 opens the circuit of the polarizing winding of the relay 51 at armature 64 and at armature 63 opens the bridge across the conductors 70 and 71 including the windings of relays 51 and 53. The removal of the bridge across conductors 70 and 71 causes the circuit of the line relay 201 of the connector H to be opened. In the connector H, relay 201, upon deenergizing, opens the circuit of the slow acting relay 202. Upon retracting its armature, relay 202 closes the circuit of the release magnet of the connector H at armature 207 and at armature 203 removes ground from the release trunk conductor thereby opening the holding circuit of the selector E. The release magnet of the connector H operates to restore this switch to its normal position and the release magnet 158 of the selector E operates to release the selector E in the usual manner. In the above manner all the apparatus involved in the connection is restored to its normal position.

Having described the operation of the repeater D, the operation of the repeater D' Fig. 1, which is a modification of the repeater D will now be briefly described. In order to do this it will be assumed that in the previous connection the operator uses a trunk circuit such as the one terminating at jack J². By the insertion of the plug P' into the jack J² a circuit is completed for the supervisory lamp L² in series with the lower winding of the sleeve relay 105 of the repeater D'. Relay 105, upon energizing, at its armature 115 closes a circuit for the polarizing winding of the electro-polarized relay 101, at armature 114 closes a point in the operating circuit extending to the in-

coming switch in the automatic exchange, and at armature 116 prepares a certain chain circuit which will be fully described herein-after. Another result of the insertion of the 5 plug P' into the jack J² is that a circuit is completed for the line relay 104 in series with the upper right hand winding of the repeating coil of the cord circuit O. Relay 104, upon operating at its armature 113 10 closes a bridge across the trunk conductors 120 and 121 through the lower winding of the electro-polarized relay 101 and through the winding of the relay 103. The electro-polarized relay 101 does not operate at this 15 time, as the current flow in its lower winding is opposite to the current flow in its upper winding. Relay 103, upon energizing, short circuits the impulse springs 113 on the line relay 104 thereby establishing a locking circuit for itself exclusive of these springs. This short circuit prevents false preliminary 20 interruptions being produced in the bridge across the trunk conductors 120 and 121 in a manner similar to that before described.

25 When the calling device is operated in accordance with the first digit of the desired number, the forward movement of a dial closes the circuit of the relay 102. Relay 102 operates in a manner similar to relay 52 30 to place a direct bridge across the trunk conductors 120 and 121. The deenergizations of the line relay 104 in response to the operation of the calling device causes the interruptions to be repeated in the line relay in 35 the incoming first selector in the automatic exchange. The first selector in the automatic exchange operates in the usual manner, being raised to the proper level of bank contacts in response to the digit dialled and then 40 rotated until its wipers are brought into engagement with the bank contacts of a trunk line extending to an idle connector switch. When an idle trunk line is found, the connection is extended to the line relay of this 45 connector switch which operates to close the circuit of its slow acting release relay. The latter relay prepares the operating circuits of the connector and establishes a holding circuit for the operated first selector in the 50 usual manner. Returning now to the operation of the repeater D', upon the calling device S' restoring to normal, the relay 102 is deenergized to replace the winding of 55 relays 101 and 103 in the bridge across conductors 120 and 121.

In response to the two succeeding operations of the calling devices S' the line relay of the repeater D' operates to repeat the impulse series to the line relay of the connector 60 in the automatic exchange. The line relay of this connector causes the switch to establish connection with the desired line in the usual manner.

When the called subscriber answers, the 65 back bridge relay in the connector energizes

to reverse direction of current flow through the bridge including the lower winding of the electro-polarized relay 101 in the repeater D'. Relay 101, upon operating at its armature 109 closes the circuit of the relay 100. Upon operating, relay 100, at armature 106 closes a locking circuit for the line relay 104 at the same time disconnecting it from the tip side of the jack J², at armature 107 disconnects the relay 102 from the ring side of the jack J², and at armature 108 removes the short circuit from the upper winding of the sleeve relay 105. By the removal of this short circuit the current flow is reduced and the lamp L² is extinguished, 70 though the relay remains energized as before. By the effacement of the lamp L² the operator is informed that the called subscriber has answered. Conversation now takes place between the calling and called subscriber in the 75 usual manner. When the conversation is terminated, the connection is released by the operator removing the plugs P and P' from the jacks J and J², respectively.

It will be seen that when the called subscriber answers all bridges are removed from the trunk line on the left hand side of the condensers and that supervision is secured over the sleeve conductor. Thus a slightly higher grade of transmission is secured by 90 using the repeater D' than by using the repeater D.

The chain circuits controlled by the relays 55 and 105 mentioned above are provided in order to eliminate unnecessary testing of 100 a large number of jacks during the busy hour and will now be described. The trunk lines are arranged in groups of tens, with a chain circuit for each group, so that the operator will receive a busy signal upon testing 105 the first jack of a group of ten if all ten trunks of the group are busy, and may next proceed to test the jack associated with the first trunk line of the succeeding group without having to test the other nine jacks in the 110 first group. To explain this a little more fully, the trunk circuit D is the first one in its group, and the relay 55, upon attracting its armature 65, closes one point in the group 115 chain circuit. If all the other trunk lines of the group are busy, armatures such as 128, 129, and 130 on other relays such as 55 will be closed and a lead from the signalling machine T will be connected to the sleeve of the jack J'.

The features of the invention having been described and ascertained, what is considered to be new and desired to have protected by Letters Patent will be pointed out in the appended claims.

What is claimed is:

1. In a telephone system, an operator's position, an automatic switch, a trunk line extending from said position to said switch, a line relay for said switch bridged across 130

said trunk line, a cord circuit at said operator's position for connecting a calling line to said trunk line, a circuit for said line relay including conductors of said trunk line, a second relay associated with said trunk line at said operator's position, means effective when said cord circuit is connected to said trunk line for energizing said second relay to close said circuit, and a third relay included in said circuit then operable to maintain said circuit closed independent of said second relay.

2. In a telephone system, an operator's position, an automatic switch, a trunk line extending from said position to said switch, a line relay for said switch bridged across said trunk line, a cord circuit at said operator's position for connecting a calling line to said trunk line, a circuit for said line relay including conductors of said trunk line, a second relay associated with said trunk line at said operator's position, means effective when said cord circuit is connected to said trunk line for energizing said second relay to close said circuit, a third relay included in said circuit then operable to maintain said circuit closed independent of said second relay, a calling device in said cord circuit, and means controlled by said calling device for deenergizing said third relay.

3. In a telephone system, an operator's position, an automatic switch, a trunk line extending from said position to said switch, a line relay for said switch bridged across said trunk line, a cord circuit at said operator's position for connecting a calling line to said trunk line, a circuit for said line relay including conductors of said trunk line, a second relay associated with said trunk line at said operator's position, means effective when said cord circuit is connected to said trunk line for energizing said second relay to close said circuit, a third relay included in said circuit then operable to maintain said circuit closed independent of said second relay to render the second relay ineffective, a calling device in said cord circuit, and means controlled in the setting of said calling device to deenergize said third relay and render said second relay effective to interrupt said circuit responsive to the operation of the calling device.

4. In a telephone system, a trunk line comprising two inductively connected sections, a line relay energized over the first section to close a bridge across the second section, and a relay included in the bridge and responsive to the initial closure thereof for closing said bridge at another point.

5. In a telephone system, a trunk line comprising two inductively connected sections, an automatic switch in which the second section terminates, a line relay energized over the first section and having contacts for closing a control circuit for said switch

over the second section, and a second relay included in said control circuit and responsive to the closure thereof for shunting said contacts to prevent the control circuit from being opened by an accidental deenergization of said line relay.

6. In a telephone system, a trunk line comprising two inductively connected sections, an automatic switch in which the second section terminates, a line relay energized over the first section and having contacts for closing a control circuit for said switch over the second section, a second relay included in said control circuit and responsive to the closure thereof for shunting said contacts to prevent the control circuit from being opened by an accidental deenergization of said line relay, a calling device for controlling said line relay over the first section to produce interruptions in said control circuit for operating said switch, and a third relay responsive to the operation of said calling device to open the shunt circuit.

7. In a telephone system, a group of jack ending trunks, circuit arrangements for placing a test potential on the sleeve of any jack when the associated trunk is busy, a tone machine, and means including a chain circuit for connecting said machine to the sleeve of the jack of the first trunk when all said trunks are busy.

8. In a telephone system, a trunk line having two talking conductors, an automatic switch terminating said trunk line, a calling device, means responsive to the actuation of said calling device and controlled over one of said talking conductors for placing a bridge across said trunk line, and means controlled over the other of said talking conductors for opening and closing said bridge for operating said switch.

9. In a telephone system, a trunk line comprising two inductively coupled sections, an automatic switch terminating the second section, a calling device, means responsive to the actuation of said calling device and controlled over one of the talking conductors of the first section for placing a bridge across the talking conductors of the second section, and means controlled over the other talking conductor of the first section for producing interruptions in said bridge to operate said switch.

10. In a telephone system, a trunk line terminating in an automatic switch, a line relay for said switch bridged across said trunk line, a circuit for said relay including the two talking conductors of said trunk line in series, a second relay, means effective when said trunk line is seized for energizing said second relay to close said circuit, and a third relay included in said circuit then operable to maintain said circuit closed independent of said second relay.

11. In a telephone system, a trunk line

- comprising two inductively coupled sections, an automatic switch terminating the second section, a line relay energized over the first section and having contacts for closing a control circuit for said switch over the second section, said circuit including the two talking conductors in series, and a second relay included in said control circuit and responsive to the closure thereof for shunting said contacts to maintain said circuit closed independent of said line relay.
12. In a telephone system, a repeater for repeating impulses over two conductors of a trunk line in series, a line relay connected across said trunk line, impulses repeating contacts in said repeater, a calling device, means for associating said calling device with said repeater, means responsive to said first means for closing a circuit for said line relay excluding said contacts, and means responsive to the actuation of said calling device for including said contacts in said circuit to control the operation of said line relay.
13. In a telephone system, a repeater for repeating impulses over two conductors of a trunk line in series, a line relay connected across said trunk line, impulse repeating contacts in said repeater, a calling device, means for associating said calling device with said repeater, means responsive to said first means for closing a circuit for said line relay excluding said contacts, means responsive to the actuation of said calling device for including said contacts in said circuit to control the operation of said line relay

and for again excluding said contacts when said calling device returns to normal.

14. In a telephone system, a switch, a relay having contacts for repeating impulses to said switch, a calling device for controlling said relay, and means responsive to a setting operation of said calling device for including said contacts in circuit with said switch.

15. In a telephone system, a switch, a relay having contacts for repeating impulses to said switch, a calling device for controlling said relay, and means responsive to a setting operation of said calling device for including said contacts in circuit with said switch and for excluding said contacts from the circuit again when said calling device has restored to normal.

16. In a telephone system, a trunk terminating in a switch, a control circuit for said switch including the two sides of said trunk in series, a relay having contacts for producing impulses in said circuit, said contacts being normally ineffective, a calling device for controlling said relay, and means responsive to a setting operation of said calling device for rendering said contacts effective.

17. In a telephone system, a group of jack ending trunks, circuit arrangements for placing a test potential on the sleeve of a jack when the associated trunk is busy, and means for giving a distinctive audible signal responsive to the testing of the first trunk when all the trunks of the group are busy.

In witness whereof, I hereunto subscribe my name this tenth day of May, A. D. 1922.

BERNARD D. WILLIS.
